SELF-LOCKING BUNDLING STRAP

George Geisinger, Elizabeth, N.J., assignor to The Thomas & Betts Co., Elizabeth, N.J., a corporation of New Jersey

Filed July 9, 1965, Ser. No. 86,096

Term of patent 14 years

(Cl. D17—5)

FIGURE 1 is a top plan view of a self-locking bundling strap showing my new design;

FIGURE 2 is a side elevation thereof;

FIGURE 3 is a bottom plan view thereof;

FIGURE 4 is a cross-sectional view taken on the line 4—4 of FIGURE 1;

FIGURE 5 is a fragmentary sectional view on an enlarged scale showing how the flexible pawl integral with the head-end of the strap coacts with the tail-end portion of the strap upon passing the same therethrough in looped relation; and

FIGURE 6 is a similar fragmentary sectional view showing how the integral, flexible pawl reacts to lock the looped body portion of the strap upon reverse relative movement thereof.

Portions of the design shown in FIGURES 1, 2 and 3 are shown broken away to indicate indefinite length.

I claim:

The ornamental design for a self-locking bundling strap, as shown and described.
